UNITED STATES PATENT OFFICE.

WALTER CHIPPERFIELD, OF HORNCHURCH, ENGLAND, ASSIGNOR TO A. B. DICK COMPANY, OF CHICAGO, ILLINOIS, A CORPORATION OF ILLINOIS.

TYPE-COMPOSING MACHINE.

1,367,302.

Specification of Letters Patent.

Patented Feb. 1, 1921.

Application filed April 27, 1920. Serial No. 377,046.

To all whom it may concern:

Be it known that I, WALTER CHIPPERFIELD, a subject of the King of Great Britain, residing at Kinkora, Great Nelmes, Hornchurch, Essex, England, have invented certain new and useful Improvements in Type-Composing Machines, of which the following is a specification.

My present invention is an improvement upon the type of apparatus disclosed in my application Serial No. 354358, type composing machines, filed January 27, 1920. In the construction described in the said application a detachable composing stick is carried by a frame which is moved by the operation of selective devices, such as the keys of a keyboard mechanism, to aline the composing stick with any desired one of the type troughs of the type font. When the composing stick has been thus alined another manually-operated mechanism is brought into play, such as one comprising a presser bar and mechanism operated thereby, which results in the bottom type contained in the selected type trough falling into the composing stick.

The operation of such a machine is made somewhat simpler and more expeditious in the construction of my present invention. The necessity of operating first one mechanism and then another, to position the composing stick and cause a type to drop into the same, is now done away with. In accordance with my present invention, I provide a single operating member which is manipulated by the operator in such manner as to both aline the composing stick with a desired type trough and to cause one type to pass from the said trough into the stick. The single operating member may position the composing stick by one movement, such as a movement of rotation in a horizontal plane and, when the composing stick has been thus positioned, may release one type from the selected type trough by a movement in another direction which is caused to set appropriate mechanism in operation.

In the form of my invention which is illustrated in the drawings, an operating lever is connected by gears to the vertical spindle which carries the frame in which the detachable composing stick is mounted. A plun-

ger is mounted in the operating lever so as to be movable at right angles thereto, this plunger constituting a handle which is grasped by the operator in positioning the lever. A plurality of key-plungers are provided, corresponding to the different type troughs, these key-plungers being passed over by the operating plunger or handle while the operating lever is being positioned. When the composing stick is thus alined with a desired type trough, the operating plunger is in alinement with the corresponding key-plunger. The operating plunger is then depressed or pressed into contact with the alined key-plunger which operates a train of mechanism comprising levers and a sliding rod, to operate the type releasing mechanism so as to cause the lowermost type in the selected type trough to fall into the composing stick. The method of operation is thus very simple, consisting simply in moving the operating plunger into alinement with a desired key-plunger and then depressing the same, the hand of the operator never leaving the single operating plunger until the composing stick has been filled with type.

The objects of my invention are to provide devices operating in accordance with the above brief description. Preferred structural details and combinations of parts embodied in my invention will appear more fully hereinafter.

In order that my invention may be more clearly understood, attention is hereby directed to the accompanying drawings forming part of this application and illustrating one embodiment of my invention. In the drawings Figure 1 represents, partly in side elevation and partly in section, a form of type composing machine embodying my invention; Fig. 2 represents a horizontal section taken on line 2-2 of Fig. 1; and Fig. 3 is a detailed view partly in side elevation and partly in section showing a modification in the construction of the operating plunger and key-plungers.

Referring to the drawings, a vertical tubular shaft 1, to which is attached a radial frame 1* carrying a composing stick 2, is supported in a bearing 3 formed in the upper face of a hollow bed plate 4. Shaft 1 has affixed to its lower end a pinion 5 which engages a segmental rack 6 carried by a ver-

tical spindle 7 projecting upwardly through the face of the bed plate 4. This vertical spindle 7 has secured to its upper end an operating lever 8 which carries a bar 9 which is slidable in a radial direction, that is, in the direction of the length of the lever 8. A vertical plunger 10 is mounted upon the outer end of the slidable rod 9, this plunger being upheld by a spring 11, and provided with a head suitably shaped to be grasped by the operator.

In the hollow bed plate 4 are mounted a plurality of vertically movable key-plungers 12 each supported by a spring 13. These plungers 12 are preferably arranged in a series of concentric arcs, as is shown in Fig. 2, and are equal in number to the type-containing troughs of the machine. Underlying the lower ends of the key-plungers 12 within the hollow bed plate 4 are two platforms 14 and 15 carried by rock levers 16 and 17, fulcrumed at 18 to lugs 19 carried by the bed plate 4. The inner ends of these levers engage with a flanged sleeve 20 slidably mounted upon the segment-bearing spindle 7.

Within the tubular shaft 1 is fitted a sliding rod 21 which projects below the end of the said shaft 1, and has affixed thereto a flanged sleeve 22. Engaging with the said sleeve is one arm of a two armed lever 23 fulcrumed at 24 to lugs carried by the bed plate 4, the other arm of the lever 23 engaging with the flanged slidable sleeve 20 referred to above.

Mechanism for releasing the type from the type troughs is indicated in Fig. 1, wherein a conical structure 25 within the ring of type troughs 26 carries a series of two armed levers 27 equal in number to the type troughs. Each lever 27 is pivoted at 28 to lugs carried by the conical structure, and one arm of each lever 27 carries a tooth 29 which extends into the bottom of the type trough 26 to which it appertains and normally prevents the lowermost type from leaving the same.

Pivoted at 30 to one arm of the lever 27 is a single armed lever 31 which has a projection 32 positioned opposite to the base of the type immediately above the lowermost type in the type trough. Each lever 31 is connected to the upper arm of its lever 27 by a spring 33, and each lever 31 has a curved tail portion 31'.

Carried upon the radial frame 1* is a plunger 34 connected to bell-crank lever 35. When the composing stick 2 has been brought to a desired position in alinement with a selected type trough, the plunger 34 is positioned opposite to the tail end 31' of the lever 31 pertaining to the selected type trough. The horizontal arm 35' of bell-crank lever 35 engages with a collar 36 slidably mounted on the tubular shaft 1, the said collar being connected to the sliding

rod 21 by means of a pin 37 carried by rod 21 and projecting through a slot in the tubular shaft 1. Type releasing mechanism of the character described is fully described and claimed in my said copending application Serial No. 345358.

In operation, the operator grasps the head of the operating plunger 10 and brings it over one of the key-plungers 12, the key-plungers being arranged concentrically with respect to the axis of the operating lever 8. With the mechanism described, such positioning of the plunger 10 is accomplished by an angular movement of the operating lever 8 and a sliding movement of the rod 9, if necessary. The key-plungers 12 are preferably located in concentric series instead of all in one arc for the purpose of economizing space and shortening the operating arc of the lever 8. The oscillation or angular movement of lever 8 results in the rotation through rack and pinion 6 and 5 of the shaft 1 and the consequent positioning of the composing stick immediately below the particular type trough desired, it being understood that the various key-plungers 12 are so positioned that the alinement of plunger 10 with any one of the same results in the positioning of the composing stick beneath the corresponding type trough. The key-plungers 12 may be suitably designated so that they will serve as indicating means so that the positioning of the plunger 10 in alinement with any one of the same will indicate that the composing stick has been brought into alinement with a trough carrying type corresponding to the designation of the key plunger referred to.

Having brought the operating plunger above the particular key-plunger desired the operator presses the operating plunger downwardly and thereby depresses the key-plunger 12 selected. This key-plunger in turn rocks the platform 14 or 15 above which it is mounted and the levers 16 or 17 carrying the platform. Sleeve 20 is slid upwardly on spindle 7 by the oscillation of levers 16 or 17 and the lever 23 accordingly rocked.

The movement of lever 23 moves the sliding rod 21 downwardly, whereby collar 36 is depressed and the lever 35 rocked, which causes the plunger 34 to rock the alined lever 31 until its projection 32 grips the next to bottom type in the type trough, this action simultaneously causing lever 27 to rock about its fulcrum and to remove its tooth 29 from beneath the lowermost type so as to allow the latter to pass into the composing stick.

The same operation will be repeated for each type required. It will be seen from the foregoing description that the operator can effect both the angular movement of the composing stick and actuate the releasing

mechanism for the type with the use of one hand only, and without having to release the operating lever.

In order to insure accuracy of position of the operating plunger 10 so that when depressed it shall automatically register coaxially with the key-plunger 12 upon which it is to operate, the acting end of the said plunger may be in the form of a cone 38 as shown in Fig. 1, and engages with a conical recess 39 formed in the heads of the plungers 12, or on the other hand the acting end of the plunger 10 may have a conical recess 40 as shown at Fig. 3, and engage with cones 41 formed on the heads of the said key-plungers 12.

It will be understood that my invention is not limited strictly to the details of construction described, but is as broad as is indicated by the accompanying claims.

What I claim is:—

1. In type composing machines, the combination of a plurality of concentrically arranged type troughs, a composing stick, means for carrying the same, comprising an axial shaft and a radial arm thereon, type releasing means, a manually operable member connected to said shaft and revoluble for alining said stick with any desired trough, means carried by said member and movable at an angle to the plane of movement thereof, and means operated by said last named means after said member has adjusted said stick into desired position, to operate said type-releasing means to release one type from the selected trough.

2. In type composing machines, the combination of a plurality of type troughs, a composing stick, means for carrying the same, a manually-operable member having movements in different planes, one of the same being a rotative movement and the other a straight line movement, means operated by said first movement of said member to aline said stick with any desired trough, and means operated by said second movement of said member to release one type from the selected trough.

3. In type composing machines, the combination of a plurality of type troughs, a composing stick, means for carrying the same, a plurality of plungers corresponding to different types, revoluble manually-operated means for moving said stick into alinement with any desired trough, means carried by said revoluble means for operating a desired plunger, said last named means being adapted to be alined with a plunger corresponding to the trough with which said stick is alined, and means operated by said plunger to release one type from the trough alined with said stick.

4. In type composing machines, the combination of a plurality of concentrically-arranged type troughs, a composing stick,

carrying means therefor, including an axial shaft, an operating member, connected to said shaft and revoluble to position said stick beneath any selected one of said troughs, a series of plungers, with any one of which said operating member may be alined when said stick is alined with a selected trough, and means operable by movement of the plunger alined with said operating member for releasing one type from the selected trough.

5. In type composing machines, the combination of a plurality of concentrically-arranged type troughs, a composing stick, carrying means therefor, including an axial shaft, an operating lever, connected to said shaft, and revoluble to position said stick in alinement with any selected trough, a keyboard, a series of key plungers thereon, means carried by said lever adapted to operate a selected key plunger, and key-plunger-operated means for releasing one type from a selected trough when said stick has been alined therewith.

6. In type composing machines, the combination of a plurality of concentrically-arranged type troughs, a composing stick, carrying means therefor, including an axial shaft, an operating lever, connected to said shaft, and revoluble to position said stick in alinement with any selected trough, a series of key-plungers, a manually-movable plunger, carried by said lever and movable at right angles to the plane of movement of said lever, said plunger moving over said key-plungers as said lever revolves and being adapted to depress any one of the same, and means operated by a key-plunger alined with said manually-movable plunger for releasing one type from a selected trough.

7. In type composing machines, the combination of a plurality of concentrically-arranged type troughs, a composing stick, carrying means therefor, including an axial shaft, an operating lever, connected to said shaft, and revoluble to position said stick in alinement with any selected trough, a rod slidably mounted in said lever to move lengthwise thereof, a manually-movable plunger carried by said rod, key-plungers in different rows, positioned to be passed over by said manually-movable plunger and operated by movement thereof, relative to said rod and lever, and means operated by a key-plunger for releasing one type from a selected trough.

8. In type composing machines, the combination of a plurality of type troughs, a composing stick, means for alining said stick with any desired trough, including an operating member, a revoluble shaft, and gear connections between said member and shaft, a depressible device carried by said member, key-plungers passed over by said device, type-releasing means movable with said

stick, and means, comprising a lever and a sliding rod, to operate said type-releasing means by the operation of any of said key-plungers.

5 9. In type composing machines, the combination of a plurality of type troughs, a composing stick, means for alining said stick with any desired trough, including an operating member, and a depressible device carried thereby, a series of key-plungers passed

over by said device, and adapted to be operated thereby, when said stick has been positioned, a lever operatively connected to all of said plungers, a sliding rod operated by said lever, and means for releasing one type 15 from a trough with which said stick is alined, upon movement of said rod.

This specification signed this 12th day of April, 1920.

WALTER CHIPPERFIELD.
